UNITED STATES PATENT OFFICE.

JOHN S. ERSKINE, OF FREEPORT, ILLINOIS, ASSIGNOR TO STOVER MANUFACTURING & ENGINE CO., OF FREEPORT, ILLINOIS, A CORPORATION OF ILLINOIS.

COAL CHUTE.

Application filed March 14, 1922. Serial No. 543,558.

To all whom it may concern:

Be it known that I, JOHN S. ERSKINE, a citizen of the United States, residing at Freeport, in the county of Stephenson and 5 State of Illinois, have invented a certain new and useful Improvement in Coal Chutes, of which the following is a specification.

This invention relates to passages through 10 exterior walls of buildings of the type commonly used for introducing coal into the building, and therefore commonly known as coal chutes, although the use of the invention is not, by any means, limited to devices 15 designed exclusively for the introduction of coal.

The object of the invention is to provide 20 a device of this class with an exceedingly simple and readily operable door adapted to close the passage when no coal or other 25 material is being introduced into the building, but adapted to swing to a position where it assists in guiding coal introduced into the building, this in combination with means 30 for protecting the door when in its latter position, should the door be made of glass or other transparent material, the protecting device being readily movable when the chute door is shut so that it does not obstruct the 35 passage of light through the transparent material of the door.

A further object of the invention is to provide, in combination with the foregoing, a 35 wall protecting shield which may be swung against the building in which the chute is placed, when the chute is in position for the introduction of coal, and to provide a single operating means operable at a distance from the chute, to selectively open or close 40 the door in the chute, as the operator may desire.

The invention consists in means capable 45 of attaining the foregoing objects which can be comparatively easily and cheaply made, which is very satisfactory and efficient in operation and which is not readily liable to get out of use. The invention further consists in many features and details of construction which will be hereafter more fully 50 set forth in the specification and claims.

Referring to the drawings, in which like numerals designate the same parts throughout the several views—

Figure 1 is a perspective exterior face 55 view of the chute mechanism of this inven-

tion, showing the door in normal or closed position;

Figure 2 is a vertical sectional or detail view through the wall of a building or the like, showing the mechanism of this invention in its preferred form applied thereto, the door and co-operating parts being in the position which they assume when the door is closed;

Figure 3 is a plan view of the mechanism 65 of Figure 2, certain parts being shown in section;

Figure 4 is a changed position view of the device of Figure 1, showing the parts in the position which they assume when coal is being introduced into the building;

Figure 5 is an enlarged detail plan view 75 of the door securing latch mechanism taken from the upper left-hand corner of Figure 3;

Figure 6 is a perspective view of the device of this invention taken from the inside of the building, with the parts in the same position as in Figure 2; and

Figure 7 is a changed position perspective 80 view of the parts of Figure 6, showing such parts in the position of Figure 4; and

Figure 8 is a section through the door showing the hinge mounting.

The chute closing door and associated 85 parts, to be hereafter fully described in detail, may, without departing from this invention, be installed in any wall opening of a building through which coal or other material is to be introduced. They are, however, most conveniently offered for sale and applied to the building, by selling them in conjunction with a ready made member 10 provided at convenient points with outwardly turned teeth 12 embeddable in the 90 wall proper, 14, of the building, the chute at the outer surface 16 of the building being closed by a rectangular door frame 18 suitably secured in place by any suitable means such as rivets 20. In ordinary practice, the 95 chute proper, 10, and the door frame 18, will be secured in place by these rivets at the factory, and the wall 14 built around the parts described. There is, however, nothing in the character of the invention to prohibit the assembling of the chute 10 and the frame 18 in connection with a previously 100 built wall 14 in which a perforation has been provided for the chute 10.

Pivoted in any suitable manner on the 110

lower side of the opening in the frame 18, as for instance on pivots 22, is a chute closing door 24 shown in the drawings as provided with a central perforation 26 closed by glass 28 or other translucent material, through which light may pass into the coal chute when the door is closed, as shown in Figures 2 and 6. There is, however, nothing in the invention to prevent a solid door being used if economy or other reason prompts the use of such a construction.

The hinges are preferably made with U-shaped lugs 19 on opposite sides of pivots 22 so arranged that the door can be lifted off the pivots when the door is partly open and set aside out of the way of objects to be inserted in the chute, should it be desired to do so, and yet cannot be removed when the door is closed.

Projecting from opposite ends of the door 24 into the chute 10 and secured to the door by any suitable means, as for instance the angles 30 and rivets 32, are suitably shaped coal guiding plates 34 connected at their outer corners, which are most remote from the door, by cross bar stop 36 adapted, when the door opens, to engage downwardly projecting lugs 38 on the inner side of the upper edge of the frame 18 and, as clearly shown in Figure 4, to limit the downward and outward movement of the door 24 to the proper angular position, best suited for insuring the ready passage of coal thrown onto the door 24 when in this position, down the door and the chute 10 into the interior of the building.

Whenever the door 24 is made with the glass insert 28 or its equivalent, a supplemental glass protecting door 40 is provided, pivoted horizontally at 42 along the bottom portion of door 24 so that it can swing from the position of Figures 4 and 7, where it covers and protects the glass window 28 when the chute mechanism is in coal introducing position, to the position of Figures 2 and 6, in which it does not in any way obstruct the passage of light entering the building through the chute 10 and the closed window 28.

When a solid chute door without glass 28 is used in place of the door 24, this glass protecting door 40 becomes functionless and may be omitted from the structure without otherwise departing from this invention.

In order to protect the lower part of the outer surface 16 of the wall 14, which is adjacent to the upper side of the chute 10 from coal dust and the like which normally arises in the operation of passing coal through the chute mechanism when the parts are in the position of Figures 4 and 7, another dust-protecting door 44 is provided, the same being, in the particular case here illustrated, secured in place by pivoting its

opposite ends on suitable pivot pins 46 inserted one each at convenient points in the two plates 34 heretofore described. This door is of such a size and shape that when the chute door is opened for the introduction of coal, it will assume the position shown in Figures 4 and 7, and thus protect the adjacent portion of the outer surface of the building wall, and at other times it may be swung to the position of Figures 2 and 6, in which it is conveniently packed inside the members 34 and does not interfere with the free movement of the door 24 and attached parts into the final closed position of Figures 2 and 6. The door mechanism 24 is normally locked in the closed position shown in Figure 2 by at least one and preferably two oppositely positioned bolts 50, each normally urged by a spring 52 into locking relation with a block 54 carried on the upper end of the adjacent angle 30 heretofore referred to, these bolts 50 being themselves reciprocatably mounted in the depending stationary lugs 38 heretofore described.

Each bolt 50 is provided at its non-locking end with a more or less unnecessary ring 56 to which is attached a branch 58 of a rope, cord or chain 60 leading from these bolts first through the stationary eyelet 62 on member 36, thence through stationary eyelet 64 at the rear of the upper inner wall of the chute 10, thence through another eyelet 66 on the member 36 and thence out of the chute 10 to a convenient point inside the building, where it may be manipulated by an operator of the device. The term eyelet is used to include pulleys or equivalent rope carrying devices. If only one latch bolt 50 is used, the branch rope not connected to it is simply attached to a stationary point on the opposite wall, i. e., member 56^a, Figure 6, can be on a bolt (not appearing) on the wall.

For purposes of description, we have placed upon Figures 2 and 4 of the drawings an imaginary line A—A passing through the pivot 22 of the door 24 and the eyelet 64 recently described. Assume that the door is closed, with the parts in the position of Figure 2 and that the operator inside the building pulls upon the free end 60^a of the rope 60. This action does two things. It first transmits to the branch members 58 of the rope 60 a tension sufficient to retract the bolts 50 from latches 54 and thus release the door 24. It also creates in the two parts of the rope 60 passing through eyelet 62, through eyelet 64, to eyelet 66, a tension tending to rock the door mechanism 24 in a counter-clockwise direction as viewed in Figure 1, to open the door and this tension continues until the bar 36 has at least passed up until its plane includes line A—A, Fig-

ure 2. Before the door 24, and its attached parts, reaches this position, however, the center of gravity of the door mechanism has, because of the excessive weight of the door 5 itself, passed to the left of the frame 18, with the result that the door will open the rest of the way by gravity. In other words, briefly stated, when the operator pulls on end 60^a of rope 60, he releases the latches or 10 bolts 50 and starts the door toward its open position with sufficient force so that the opening movement is completed by the weight of the door 24 in that portion of the opening stroke of the door in which member 15 36 is above line A—A, as viewed in Figure 2. Conversely, when the chute door mechanism is open, as viewed in Figure 4, and the operator starts to pull on end 60^a of rope 60, he exerts, in the manner which is entirely 20 obvious from an inspection of Figure 4, a horizontal pull on the bar 36, which will move the door mechanism in a clockwise direction until this member 36 passes line A—A of Figure 4. By giving the rope end 25 60^a a sharp jerk, the operator can, while the door is moving this far, give the door mechanism sufficient momentum so that after bar 36 crosses line A—A, the door will complete its closing operation without other manual 30 assistance.

From the foregoing, it appears that with the door mechanism either open or closed, the operator inside the building can, by pulling more or less sharply on the one single 35 rope 60, cause the door mechanism to close or open as the case may be.

Attention is called to the fact that while, in the particular construction shown, door 44 must be moved by hand to its elevated 40 wall protecting position, it is automatically thrown to its folded-in position by the closing of the chute door.

The word "rope" as used in the claims is intended to mean any chain, flexible wire, or 45 other equivalent pulling device.

What I claim is:

1. In mechanism of the class described, in combination with a chute having one end to be closed, a door pivoted to swing to two 50 different positions, in one of which it closes said chute and in the other of which it is inclined thereto for the reception of material to pass through the chute, and a single operating mechanism located at a distance 55 from the chute end which is opposite to the door, adapted for manipulation by an operator to open or close the chute door as the case may be.

2. In mechanism of the class described, in 60 combination with a chute having one end to

be closed, a door pivoted to swing to two different positions, in one of which it closes said chute and in the other of which it is inclined thereto for the reception of material to pass through the chute, and a single 65 rope adapted to be pulled by an operator at a distance from the end of the chute which is opposite to the door, to open or close the chute door as the case may be.

3. In mechanism of the class described, in 70 combination with a chute having one end to be closed, a door pivoted to swing to two different positions, in one of which it closes said chute and in the other of which it is inclined thereto for the reception of material 75 to pass through the chute, means latching the door in closed position, and a single rope adapted to be pulled by an operator at a distance from the end of the chute which is opposite to the door to release said latching 80 means and open or close the chute door as the case may be.

4. In mechanism of the class described, in 85 combination with a chute having one end to be closed, a door pivoted to swing to two different positions, in one of which it closes said chute and in the other of which it is inclined thereto for the reception of material to pass through the chute, means mounted on 90 stationary supports in the chute latching the door in closed position, and a single rope adapted to be pulled by an operator at a distance from the end of the chute which is opposite to the door to release said latching 95 means and open or close the chute door as the case may be.

5. In mechanism of the class described, in 100 combination with a chute having one end to be closed, a door pivoted to swing to two different positions, in one of which it closes said chute and in the other of which it is inclined thereto for the reception of material to pass through the chute, means mounted on 105 stationary supports in the chute latching the door in closed position, an arm extending from the door into the chute and movable with the door, and a single rope having one end attached to said latch mechanism and thence slidably passing first over a fixed point on said arm, second over a fixed point at the inner end of the chute and third over another fixed point on said arm, the whole so arranged that the rope may be pulled by an operator at a distance from the end of the chute which is opposite to the door to release 110 said latching means and open or close the chute door as the case may be.

In witness whereof I have hereunto subscribed my name.

JOHN S. ERSKINE.
